UNITED STATES PATENT OFFICE.

WILLIAM FARNELL MARBLE, OF HAVERHILL, MASSACHUSETTS.

CLAMP.

Application filed April 1, 1921. Serial No. 457,530.

To all whom it may concern:

Be it known that I, WILLIAM F. MARBLE, a citizen of the United States, residing at Haverhill, in the county of Essex and State of Massachusetts, have invented a new and useful Clamp, of which the following is a specification.

This invention has reference to clamps, and more particularly to a clamp especially designed for use in the manufacture of 10 boots, shoes or the like.

The primary object of the invention is to provide a clamp having novel means to cause the same to automatically adjust itself to the article under operation.

A further object of the invention is to provide a clamp which may be used with efficiency in connection with securing the usual wooden heels to boots, shoes or the like, and eliminating all danger of splitting the heel during the securing operation.

A still further object of the invention is to provide a support for the clamp, whereby the clamp may be held against movement to insure against the article supported by the clamp becoming displaced therefrom.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, may be made within the scope of what is claimed, without departing from the spirit of the invention.

Referring to the drawing:—

Figure 1 illustrates a perspective view 40 of a clamp constructed in accordance with the present invention, showing the same as supporting a shoe.

Figure 2 illustrates a sectional view taken 45 on line 2—2 of Figure 1.

Figure 3 illustrates a plan view of the base or support of the clamp.

Referring to the drawing in detail, the reference character 5 designates the base 50 or support of the clamp and as shown this base is provided with opposed ribs 6 which have their adjacent faces inclined as indicated at 7 to accommodate the inclined surfaces of the lower jaw 8 of the clamp.

This base 5 may be secured to a bench, table or the like in any suitable manner,

as by means of the screws 9 which pass through the base 5 and embed themselves in the surface of the bench on which the device is positioned. 60

The clamp proper comprises an upper arm 10 and a lower arm 8, which arms are formed integral with the arm 11, there being provided a hook member 12 adjacent to the rear of the lower jaw 8, by means of 65 which the clamp may be hung from a suitable support, which is in the form of a relatively flat bar. This hook member is shown as lying in proximity with the rear surface of the arm 11 so that the hook may 70 cooperate with the rear surface to grip the supporting bar and prevent lateral movement thereof.

The arm 10 is provided with an enlargement 13 at one end thereof, which is formed 75 with a threaded opening to accommodate the screw 14 having a ball 15 formed on one end thereof, which ball is seated in a suitable socket formed in the head 16 and by means of which the head may pivot 80 with respect to the screw 14.

Extending upwardly from the lower arm 8, is a finger 17 formed with a rounded end 17' which rounded end is of a diameter greater than the diameter of the usual last 35 thimble, the last, positioned in a shoe, and which in the present drawing is indicated at 18.

Thus it will be seen that due to this construction the last will rock on the finger, 90 when pressure is brought to bear on the screw 14, to the end that the shoe and its last will automatically align itself between the arms 10 and 8 to insure an even pressure being directed to the heel under operation. 95

In the use of the clamp, it might be stated that the same is employed for securing the usual wooden heels to the shoe proper, there being applied a coating of 100 cement to the shoe engaging portion of the heel prior to the positioning of the same.

After the coating of cement has been applied, the shoe is positioned in a clamp in a manner as illustrated by Figure 1 of the 105 drawing, the screw 14 being operated to cause the same to force the heel to the shoe.

When the shoe has been positioned, the clamp is removed from its base and hung 110 on a suitable supporting bar not shown, whereupon the base may be again used for

supporting a clamp while a heel is being applied to a shoe, supported thereby.

Having thus described the invention, what is claimed as new is:—

- 5 1. A shoe clamp including a curved body portion having parallel arms, one of said arms having an enlargement formed with a threaded opening, a finger extending upwardly from the opposite arm, said finger having a rounded outer end and being of a diameter greater than the diameter of a last thimble to cause a last supported by the clamp to automatically adjust itself, and means cooperating with the finger for 10 clamping a heel.
2. In a shoe clamp, a body portion, a pair of parallel arms, an adjustable screw operating through one of the arms and having a movable head on one end thereof, a 15 finger extending upwardly from the opposite arm having a rounded end, the finger being of a diameter greater than the diameter of a last thimble, the rounded head of the finger adapted to engage a last thimble

adjacent to the open end thereof, to permit 25 the last to rock on the finger, and said screw adapted to engage the heel of a shoe positioned on the last to force the heel into close engagement with the shoe, and a base to removably receive the body portion. 30

3. In a shoe clamp, a body portion, a base to removably receive the body portion, said body portion including opposed arms, means carried by the arms for gripping a shoe positioned between the arms, and a 35 hook member formed integral with the body portion and disposed in spaced relation with the rear edge of the body portion, said hook member being adapted to be positioned over a supporting bar. 40

In testimony that I claim the foregoing as my own, I have hereto affixed my signature in the presence of two witnesses.

WILLIAM FARNELL MARBLE.
